UNITED STATES PATENT OFFICE.

EDWIN E. WOLF, OF NEW YORK, N. Y., ASSIGNOR TO COLONY CLUB FROCKS, OF NEW YORK, N. Y., A CORPORATION OF NEW YORK.

DESIGN FOR A DRESS.

Application filed November 6, 1923. Serial No. 7,696. Term of patent 3½ years.

To all whom it may concern:

Be it known that I, EDWIN E. WOLF, a citizen of the United States, and a resident of the city of New York, borough of Manhattan, in the county and State of New York, have invented a new, original, and ornamental Design for a Dress, of which the following is a specification, reference being had to the accompanying drawing, forming part thereof, wherein the dress is distinguished by means of an ornamental checker formation 1 matching with checker formations 2 and 3 presenting cuff structures and a checker formation 4 presenting an ornamental trimming at the bottom of the skirt. The design is further distin-

guished by the arrangement of buttons 5 with corresponding loops 6 along opposite edges of the front opening and along a line extending downwardly from the front opening to a point near the checker formation 1.

In the accompanying drawing—

Figure 1 is a front view of a dress, showing my new design.

Figure 2 is a rear view of the dress shown in Figure 1.

I claim:—

The ornamental design for a dress, substantially as shown and described.

EDWIN E. WOLF.
